UNITED STATES PATENT OFFICE.

RANDOLPH CROMPTON, OF WORCESTER, MASSACHUSETTS.

LOOM.

SPECIFICATION forming part of Letters Patent No. 739,651, dated September 22, 1903.

Application filed April 28, 1900. Serial No. 14,739. (No model.)

To all whom it may concern:

Be it known that I, RANDOLPH CROMPTON, of Worcester, county of Worcester, State of Massachusetts, have invented an Improvement in Looms, of which the following description, in connection with the accompanying drawings, is a specification, like letters on the drawings representing like parts.

The invention to be hereinafter described relates to that class of looms wherein filling-changing mechanism is employed to supply fresh filling without stopping the loom, and more particularly to such type of looms employing drop or shifting shuttle-boxes for supplying different characters or colors of filling.

It has heretofore been proposed in the class of looms employing shifting shuttle-boxes on one side thereof to effect a change in the filling when that in an active shuttle has become substantially exhausted or broken, in which event mechanically-operated means were set in action to eject the filling carrier or shuttle which had become practically exhausted or the filling of which had been broken and to replace it by a filled carrier or shuttle at the single-box side of the loom. It has also been proposed in a single-shuttle-box loom, or one using only one character or color of filling, to employ devices to effect a change of the filling when that in an active shuttle has approached exhaustion to a predetermined amount.

In my present invention I have sought to improve upon that type of looms wherein drop or shifting shuttle-boxes are employed at both sides thereof and to combine in such type of loom means whereby a fresh supply of filling may be effected when that in any shuttle has approached exhaustion to a predetermined amount. In adapting such mechanism to the character of loom specified I have found it desirable to locate the filling-changing mechanism at one side of the loom and the detecting or feeler mechanism at the opposite side thereof, both such mechanisms, however, being positioned adjacent to the shifting shuttle-boxes on its respective side, by which I am enabled to secure more time from the instant of detection of practical exhaustion of the filling and the action of the filling-changing mechanism and consequent

avoidance of shocks and imperfect operation due to quick action.

In the particular embodiment of my invention as herein exemplified I have selected a form of worsted-loom having four celled shifting shuttle-boxes at each side thereof; but it is evident, of course, that the shifting shuttle-boxes may contain any desired number of cells, and while I have selected as an illustration of my invention a filling-changing mechanism for ejecting a practically exhausted filling-carrier from the shuttle and placing therein a filled carrier it is to be understood that instead of changing the carriers I may change the shuttles.

Since the shifting shuttle-boxes contain different characters or colors of filling, it is essential that the filling-carriers in the hopper or feeder shall be arranged in groups to correspond therewith, and as the said boxes rise and fall under the call of the pattern being woven the feeder is given a motion in unison with said boxes to always maintain the proper filling in position to be placed in its proper shuttle, and in case of a practical exhaustion of the filling in an active shuttle and upon the operation of the filling-changing mechanism to supply fresh filling the feeder is automatically moved a distance sufficient to bring into operative position a new group of filling-carriers in a manner similar in general operation to that set forth in the patent to Wyman and Crompton, No. 600,053.

My invention comprehends, broadly, changing the filling-carrier in looms having two sets of shuttle-boxes, however constructed, as thereby the facility of changing filling without stopping the loom is carried out effectually in a class of loom for weaving goods where a single pick of a desired color or any uneven number of picks of a desired color can be obtained, which is of very material advantage and which makes the automatic loom, which is only recently adopted on single-shuttle weaving, capable of weaving the highest grades and most intricate patterns.

Referring to the drawings, Figure 1 is a view in side elevation of a loom embodying my invention. Fig. 2 is a front view thereof, the central portion being broken away to avoid complication in the figure. Fig. 3 is a plan view of the parts shown by Fig. 2. Fig.

4 is a side elevation of the loom opposite that shown by Fig. 1. Fig. 5 is a detail view, partly in section, of the means for operating the feeder to bring a new group of carriers 5 into operative position after a change of filling has been effected. Fig. 5^a is a sectional detail of said means on line 5^x of Fig. 5, also showing the sprocket-wheel. Fig. 6 is a detail side view of the shuttle-box motion. Fig. 10 10 is an edge view of the parts shown by Fig. 6. Fig. 8 is a detail front view of the drop-boxes and guides therefor on the lay. Fig. 9 is a like detail of parts shown by Fig. 8 in plan view. Fig. 10 is a section on the line x 15 of Fig. 9. Fig. 11 is a top view of the shuttle-boxes on a smaller scale, showing the disposition and arrangement of the contacts with respect to the binders. Fig. 12 is a top view of one form of shuttle that may be employed. Fig. 13 is a sectional detail on line y y of Fig. 20 11. Fig. 14 is a sectional detail view of the feeder-operating gearing.

The loom-frame A, breast-beam A', picker-sticks A⁴, lay A², driven from the crank-shaft 25 B' by the pitman A³, the cam-shaft B, the gears B² B³, connecting the crank and cam shafts, the filling-feeder B⁴, and the transfer- 30 35 rer B⁵, pivoted at B⁶, are and may be all as heretofore employed—as, for instance, in the construction disclosed by Patent No. 600,053, to which reference may be had. Pivotally connected to the loom-frame at b', Fig. 4, is a lever b, which carries at one end a pin or roller b², bearing on the surface of a cam B⁷, secured to the cam-shaft B, and at its opposite end has pivoted thereto at b⁸ an actuator b⁴, which is thus under normal running conditions of the loom reciprocated in a path beyond the end of the arm b⁵ secured to the 40 45 shaft d, journaled in suitable bearings attached to the loom-frame. Mounted upon a bracket b⁶, secured to the loom-frame on the side thereof adjacent the actuator b⁴, is an electromagnet b⁷, whose armature b⁸ is normally spring-pressed away from the magnet and carries at its free end an arm b⁹, which loosely embraces the upper end of the actuator b⁴, as best seen in Figs. 2 and 4. Secured to the opposite end of the shaft d, which 50 55 extends across the loom-frame, preferably below the breast-beam A', is a lifter d', carrying a pin d², which extends beneath a dagger d³, pivoted at d⁶ to the end of the arm d⁵, secured to or formed as a continuation of the transerrer B⁵.

Mounted on a moving part of the loom, preferably the lay A², is a bunter d⁴, which in the forward movement of the lay travels in a path above the end of the dagger d³; but should said dagger be raised by the pin d² on the end of the lifter d', the bunter will strike the dagger. From this construction it will be seen that should the electromagnet be energized it will attract its armature b⁸ and 60 65 move the end b¹⁰ of the actuator into position to engage the free end of the arm b⁵ on its upward reciprocation to thereby turn the

shaft d and cause the lifter d' to raise the dagger d³ into the path of the bunter d⁴ and cause the transerrer B⁵ to be operated to effect a change of filling on the forward movement of the lay.

Secured to the shuttle-box guide I on the side of the loom opposite the filling-changing mechanism are a pair of contact-plates or 75 electric terminals c c, Fig. 2, properly insulated from each other and the loom-frame in any suitable manner and in circuit with the electromagnet b⁷ by the wires or other conductors c² c², which derive electric energy 80 from any suitable source of electric supply, as the battery P, Fig. 3.

It will be noted that while there are four or more cells in the set of drop-boxes only a single pair of contact-plates or terminals 85 c c are employed, and these are shown as arranged on the said shuttle-box guide I on a line with the race or in position to co-operate with the detecting mechanism of the active shuttle for the time being, which will 90 now be described. Each cell of the shuttle-box on the detecting or right-hand side of the loom, as shown in Fig. 2, is provided with a binder c³, pivoted at c⁴ and acted on by any usual form of binder-spring c⁵, Fig. 11. Secured to each binder c³ are a pair of contact-fingers c⁶, the ends c⁷ of which project beyond the end of the shuttle-box in position to contact with the plates c c on the shuttle-box guide I. At their opposite ends these contact-fingers, as shown by Fig. 13, project through the binders c³, from which they are insulated by suitable insulating material c⁸ and are provided on the inside of the binders with conducting-plates c⁹, adapted to contact with suitable contact-plates c¹⁰ c¹⁰ on the shuttles C', Fig. 12. Each shuttle is provided with a pair of detectors c¹¹ in electric connection with the plates c¹⁰ c¹⁰, and the filling-carriers are each provided with a conductor or other ring c¹², which in the filled carrier is covered by the yarn or filling. From this construction it will be evident that so long as the carrier in an active shuttle is provided with a proper amount of filling the 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930

effect a change of filling, and this is done by providing the arm b^5 with a downturned end b^{11} , which as the indicating-shuttle is about to be picked from the indicating-box engages the upper end b^{10} of the actuator and retains the two in operative engagement. Should the drop-boxes containing a practically exhausted shuttle be changed, however, so as to take the indicating-shuttle out of the line of the race, and therefore out of position to be picked to the changing side of the loom, such changing movement of the drop-boxes taking place between the picks, the boxes receiving, preferably, about one-half their movement in the forward movement of the lay, the remaining movement of the boxes taking place during the backward movement of the lay, will carry the contact-fingers c^6 c^8 away from the contact-plates c and interrupt the circuit, the relative movement of the actuator and drop-boxes being such that the latter will disengage the contact-fingers c^6 from the plates c just prior to the upward reciprocation of the actuator; but the boxes at the filling-changing end of the lay will not be started and moved in unison with those at the detecting end of the lay, but rather the boxes at the filling-changing end of the lay will remain stationary as to their vertical movement during the forward movement of the lay, they being shifted at a faster speed during the backward movement of the lay, thus affording plenty of time to break the electric current, as will be herein-after more fully explained.

35 Mounted on each end of the lay are the drop-boxes E E' , comprising any convenient number of cells to supply the desired character or colors of filling. The boxes are carried on any usual box-rods, as E^2 , by which 40 the boxes are raised and lowered under the call of a pattern and through mechanism of any desired character to impart the motions hereinafter described. Drop-boxes rise and fall during the interval between the picks, 45 about one-half the movement taking place during the forward movement of the lay, and while this character and timing of motion is unobjectionable on the detecting side of the lay I have found it necessary to modify the 50 same on the filling-changing side in order to correctly position the shuttle-box to effect the change of filling as the lay approaches its forward position, and to this end I have provided mechanism which, while imparting the usual movement of the drop-boxes on the 55 detecting side of the lay, as above indicated, will hold the boxes on the filling-changing side of the lay stationary as to their shifting movement during the beat up, then shift them 60 rapidly on the backward movement of the lay. To effect the character of movements described, I have selected for the present embodiment of my invention the form of shuttle-box motion fully set forth in the patent to 65 Crompton and Wyman, reissued January 1, 1884, No. 10,433, to which reference may be

had, although the invention is not necessarily limited thereto.

The main levers E^3 , pivoted at E^4 and connected to the shuttle-box rod E^2 at E^5 and 70 the shuttle-box rod on the opposite side of the loom through the flexible connections e , passing over guide-pulleys e' , the secondary levers E^8 , pivoted to levers E^3 at E^9 and adapted to be acted upon by two studs or 75 pins E^{10} and E^{13} , secured, respectively, to the pin or stud carriers E^6 and E^{26} , pivoted at E^7 and shown as radius-bars, the connecting-rods E^{11} E^{14} , connected at E^{12} E^{12} to said 80 stud-carriers and to the vibrator-gears E^{16} , 85 carried on the vibrator-arms E^{14} , pivoted to the loom-frame at E^{15} , the said vibrator-arms E^{14} being under control of a pattern-surface (not shown) to raise and lower them, and the mutilated cylinder-gears E^{17} , driven from the 85 gear E^{27} by the well-known Geneva stop-movement and with which the vibrator-gears 90 E^{16} are adapted to engage under the call of the pattern-surface, are and may be all as fully disclosed in the said Reissue Patent No. 90 10,433 referred to and need not be further described.

The vibrator-catch E^{18} , pivoted at E^{24} and adapted to be moved into position to engage between the beveled ends E^{19} of the raised 95 and lowered vibrators by the rod E^{20} , having the slotted end E^{22} embracing and guided by the projecting end of the cam-shaft B , carrying the cam E^{25} , against which the roller E^{23} bears under the stress of the spring E^{21} , are 100 and may be all as heretofore and as described in United States Patent No. 405,645. The motion thus imparted to the drop-boxes by the mechanism as described would be a rising-and-falling movement between the picks and 105 during the forward movement of the lay, as disclosed in the patents referred to; but, as has been pointed out, such movement for the drop-boxes on the filling-changing side of the lay would serve to improperly position the 110 boxes with relation to the filling-changing mechanism, whereby the drop-boxes on the filling-changing side of the lay are given a quick rising-and-falling movement only on the back stroke of the lay, as I will now describe. 115

Having reference more particularly to Figs. 6 and 7, the cylinder-gears E^{17} for operating the drop-boxes on the detecting side of the lay are mounted loosely on studs e^2 , and said 120 gears have secured to them gears e^3 e^3' . The gear e^3 is engaged and driven intermittently by the usual double-acting gear E^{27} , fast on shaft B , driven in usual manner. The gear e^3 engages intermediate gears e^5 and e^4 of 125 usual form and rotate the gear e^3' and its attached cylinder-gear E^{17} . The cylinder-gears E^{17} have mounted alongside of them loosely on the studs e^2 independent cylinder-gears E^{17}' , having attached gears e^6 with one tooth 130 omitted. (See Fig. 6.) Suitably journaled in bearings, preferably above and below the

cylinder-gears E^{17} and $E^{17'}$, are the idle-shafts e^8 $e^{8'}$, each having secured to one end thereof a gear e^9 and at the opposite end a gear e^{10} , from one-half of whose surface the teeth are omitted. The gears e^3 , e^4 , e^5 , $e^{3'}$, and e^9 are preferably of the same size, while the gears e^{10} are double the size of the gears e^6 , with which they intermesh on each full rotation. The gears e^3 and $e^{3'}$ rotate the gears e^9 in opposite directions and turn with them the shafts e^8 , suitably supported by brackets connected with the framework, rotating with said shafts the connected gears e^{10} , the latter having teeth extended about half-way around. The gears e^{10} are the drivers for the independent cylinder-gears $E^{17'}$. From this construction it will be obvious that the rotation of the cylinder-gears E^{17} as derived from the gear E^{27} will be as usual and the vibrator-gears E^{16} engaged thereby and operatively connected with the drop-boxes on the detecting side of the loom will be moved with the usual slow motion between the picks and as the lay moves forward. During such movement of the cylinder-gears E^{17} the independent cylinder-gears $E^{17'}$ will remain stationary until the gears e^{10} are, through the gears e^9 , moved about a half-revolution, when the teeth of gears e^{10} will engage the gears e^6 and owing to their size will rotate said gears e^6 and their connected cylinder-gears $E^{17'}$ rapidly during the other half of the rotation of the gear e^{10} , at which time the lay is moving backwardly.

The vibrator-gears E^{16} for moving the drop-boxes on the detecting side of the loom are arranged to engage the cylinder-gears E^{17} , while the vibrator-gears $E^{16'}$ for operating the drop-boxes on the filling-changing side are arranged to be engaged with the gears $E^{17'}$, from which it will be seen that as the lay starts forward the cylinder-gears E^{17} through the usual operating devices will, if any of the vibrator-gears be in mesh therewith, commence to move the drop-boxes on the detecting side of the loom; but as at this time the cylinder-gears $E^{17'}$ are stationary by reason of the omitted teeth in the gear e^{10} the drop-boxes on the filling-changing side of the loom will not be raised or lowered. As the lay starts back, however, the teeth of gears e^{10} engage the gears e^6 and rapidly rotate the connected cylinder-gears to thereby impart rapid rotation to any vibrator-gear in mesh therewith and consequent rapid movement of the drop-boxes on the filling-changing side of the lay.

In order that the gears e^6 may be held in the position they assume as the blank portions of the gears e^{10} are passing, I provide on the idle shafts e^8 $e^{8'}$ the concave blocks e^{12} , of usual construction in such cases, which bear frictionally upon corresponding-shaped bosses on the hubs of the gears e^6 to thereby insure that the teeth of the gears e^6 shall be in position to be engaged by the teeth of the gears e^{10} .

The filling feeder or hopper B, as hereto-

fore explained, is provided with the filling carriers d^7 , arranged in groups corresponding to the characters or colors of filling in the shuttle-boxes, as fully set forth in United States Patent to Wyman and Crompton, No. 600,053, and the necessary movements to maintain said feeder in position to present a proper character or color of filled carrier to replace that in a practically-exhausted shuttle during the rise and fall of the drop-boxes and to move said feeder so as to present a new group of filled carriers in position to be acted on by the transfferer after a change of carriers has taken place is as follows: Mounted in suitable bearings formed in a bracket f , secured to the loom-frame and so as to have free rotative movement therein, is a short-shaft f' , having fixed thereto a sprocket-wheel f^2 and a bevel-gear f^3 , Fig. 14. Loosely carried by the shaft f' is a pinion f^4 , which is in engagement with a pinion f^5 , carried by a stud f^6 , Fig. 1, on the bracket f and interposed between the pinion f^4 and a similar pinion f^7 , secured to the feeder or hopper B⁴. Also loosely mounted on the shaft f' and located, preferably, between the pinion f^4 and sprocket-wheel f^2 is a pinion f^8 , having a beveled-gear face f^9 , which engages with the teeth of a bevel-gear f^{10} , carried on a stud or screw-pin f^{11} , secured to a flange or bracket f^{12} on the side of pinion f^4 , the periphery of the bevel-gear f^{10} being carried through a suitable opening f^{13} in the pinion f^4 and its teeth also engaging the teeth of the bevel-gear f^3 . The peripheral teeth f^{14} of the gear f^8 are in engagement with the teeth f^{15} of a rack-bar f^{16} , which at its lower end, as in Fig. 1, is connected to the main shuttle-box lever E^3 . Rotatively mounted on a stud g , secured to the loom-frame, is a sprocket-wheel g' , and connecting said sprocket-wheel g' and the sprocket-wheel f^2 on the shaft f' is a sprocket-chain g^1 . Mounted on or secured to the hub of the sprocket-wheel g' is a pinion g^3 , having one or more teeth in its periphery omitted, Figs. 5 and 5^a, and pivotally mounted on the face of said pinion by the stud g^4 is a yoke g^5 , the arms of which carry the teeth g^6 , said arms being adapted to swing in a plane substantially at right angles to the face of the pinion on the stud g^4 to project first one and then the other of the teeth g^6 into the space g^7 of the omitted teeth of the pinion, a catch g^8 , carried on an arm g^9 , pivoted to the face of the pinion at g^{10} and actuated toward the arm g^5 of the yoke by a spring g^{11} , serving to hold the yoke by engaging one or the other side of said yoke in either of its positions toward or away from the face of the pinion and yet permit said yoke to be swung on its stud g^4 under the impulse of an arm g^{12} , connected to the yoke, as at g^{13} . The said arm g^{12} is carried by a sleeve g^{14} , supported by a stud g^{15} , secured to the loom-frame, and said sleeve has a projecting crank-arm g^{16} , to which a rod g^{17} is connected, the opposite end of said rod g^{17} being secured to the tailpiece g^{18} , fixed to

or movable with the transerrer B⁵, as seen in Fig. 1. Mounted to freely rotate on the stud h is a pinion h', Fig. 5, which is in mesh with a pinion h², secured to the crank-shaft B', and 5 preferably secured to the face of the pinion h' is a smaller pinion h³, a portion of the teeth of which, as at h⁴, are omitted. These pinions are so located and timed in their movements as that when the lay moves forward 10 and a change of filling is taking place the teeth of the pinion h³ are in position to engage with the tooth g⁶ of the yoke g⁵, which tooth by the movement of the transerrer, the rod g¹⁷, and connected parts has been moved 15 into the space of the omitted teeth in the pinion g³. From the mechanism as thus described it will be seen that so long as the transerrer is not actuated to effect a change of filling the pinion g³, sprocket-wheel g', 20 sprocket-chain g², and consequently the sprocket-wheel f², fast on the shaft f', will remain stationary. Under these conditions should the drop-boxes on the filling-changing side of the loom rise or fall under the call of 25 the pattern and by virtue of the shuttle-box motion, as already explained, they will cause a corresponding movement of the rack-bar f¹⁶, which being in engagement with the teeth f¹⁴ of the loose gear f⁸ will rotate said gear on 30 the shaft f', and such motion will be transmitted to the pinion f⁴, and consequently to the filling - feeder, to rotate it the proper amount corresponding to the movement of the drop-boxes through the bevel-pinion f¹⁰, carried 35 by the pinion f⁴ and meshing with the then stationary bevel-pinion f³ on the shaft f'. If, however, the detecting mechanism on the opposite side of the loom has indicated a practically exhausted condition of an active 40 shuttle and said shuttle remains in action to be returned to the filling-changing side of the loom on the next pick, the dagger will be raised, as heretofore explained, to be struck by the bunter when the shuttle has reached 45 the filling-changing side of the loom, the drop-boxes on that side will not be raised or lowered as the lay moves forward, and the transerrer will be actuated to effect a change of filling. The movement of the transerrer 50 will through the rod g¹⁷ and connected yoke g⁵ move a tooth g⁶ of the yoke to fill the blank space in the pinion g³ and cause the same and connected sprocket-wheel g' to be rotated by the pinion h³ and through the sprocket- 55 chain g² to rotate the shaft f'. The gear f⁸ being held stationary at this time by the rack-bar f¹⁶, the bevel-gear f³ will act upon the bevel-gear f¹⁰ to turn the pinion f⁴, and consequently the filling-feeder, the requisite 60 distance to bring into position another group of filling-carriers, as will be obvious.

In order to hold the rack-bar f¹⁶ in position of engagement with the gear f⁸, there is secured to the loom-frame a light bracket k, 65 carrying a roller k', upon which the smooth edge of the rack-bar may move.

In the present form of my invention I have

shown the filling-carriers as adapted to be changed in the shuttle on practical exhaustion of the filling, a form of shuttle and carrier being represented in Fig. 12, wherein the filling-carrier i' is shown as retained within the shuttle by the spring-arms i i, and I have also constructed and adapted the parts of the filling-changing mechanism to eject 75 the practically exhausted carrier from the rear of the box and insert a filled carrier from the front thereof. In this form of construction and adaptation of parts I have found it preferable to dispense with the separate 80 binders for each of the shuttle-boxes on the filling-changing side of the loom and to employ a single binder substantially on the line of the race to act upon any one of the boxes of the series as they rise or fall to position 85 to receive the active shuttle.

Referring to Figs. 8, 9, and 10, the drop-boxes on the filling-changing side of the loom are designated generally by the reference-letter E, and they consist, essentially, of a series of shelves or platforms to form cells i² for the reception of the series of shuttles, said cells being open at front and rear for the passage therethrough of filling-carriers. Each cell has at its rear edge a suitable 95 flange i³ to properly bear against the shuttles and retain them from falling backward from the boxes as the lay moves. The drop-boxes on both sides of the loom rise and fall under the control of the box- motion, as heretofore explained, and are guided in such movement by suitable guideways i⁴ i⁴, formed in the box stands or brackets I, carried by the lay. Suitably hinged to the outer bracket I on the filling-changing side of the loom, Fig. 10 100 8, as at i⁵ i⁵, is a binder i⁶, having a slot i⁷ therein, as shown, and upon the free end of said binder a spring i⁸ bears to give the necessary binding action on the shuttles as they enter and leave the box. It will be 105 noted that the binder i⁶ is hinged to the box stand or bracket and does not move up and down with the shuttle-boxes; but as each successive box arrives on the line of the race it is then in position to receive the retarding 110 effect of the binder on the then active shuttle. To prevent the shuttles falling forward out of the boxes as the lay moves back, I provide guides i⁹ and i¹⁰, which are secured by appropriate screws i¹¹ to brackets i¹² i¹², attached to or formed as a part of the box stands or brackets I. These guides i⁹ and i¹⁰ preferably pass through the series of boxes and present a flange i¹³, behind which the nose of the shuttle rests when its box is not on a line with 120 the race. Since the guides i⁹ and i¹⁰ pass through the shuttle-boxes and would as a consequence be in the path of movement of the active shuttle if continued through the entire series, the said guides are interrupted at the 125 line of the race, as shown at i¹⁴, to permit the free entrance and exit of the active shuttle, and the adjoining ends i¹⁵ i¹⁵ of the guides are turned or bent toward the reed in order to

provide a positioning device for the shuttle as the boxes rise or fall in case the shuttle has not been properly boxed. If desired, the same form of guides may be employed at 5 the other end of the drop-boxes; but in the present instance I have shown guides at this end of the boxes as simple guide-strips i^{16} , secured to the box-stand I, and behind which the nose of the shuttle rests, as indicated in Figs. 8 and 9. It is obvious, of course, that the form of guides may be varied as desired without departing from the spirit of my invention. Since the drop-boxes rise and fall past the binder i^6 , I have 10 provided the boxes with a guide-strip L, on which the free end of the binder i^6 rests, said strip being provided with raising-cams l , which serve to release the binder from its contact with the shuttle as the boxes are raised and 15 lowered, thus permitting a more free action and movement between the parts during the shifting of the shuttle-boxes. The opening i^7 in the binder i^6 serves as a passage through 20 which the filling-carriers are passed as the transerrer effects the change, and the edges of the opening i^7 are preferably beveled or rounded, as at i^{17} , to obviate any sharp angles or edges to the filled carrier as it is pushed 25 into the shuttle.

30 The picker M is arranged to slide on double picking-rods m m , located, preferably, above and below the position occupied by the active shuttle in the box-cell, such position of the shuttle in which the filling is to be 35 changed enabling the ejected carrier to be pushed through the open rear side of the cell on the shuttle-box. The pickers may be provided with any usual or desired form of buffer-spring m' and have a perforation m^2 there- 40 in for the entrance of the end of the picker-staves A^4 .

It will be noticed from the construction described that the shuttle-boxes at the detecting-side of the loom are each provided with a 45 binder, and each binder has, as shown, two connected insulated contact-fingers, which as the boxes rise and fall move over contact-plates c c in electric circuit with the magnet b^7 . These contact-plates are fixed to the box-guideway I in position to coöperate, with only 50 the fingers of the binder coöperating with the active shuttle, so said fingers will not be joined in complete circuit except when an active shuttle has become exhausted to a pre-determined amount.

55 I believe that I am the first to supply different fillings to a plurality of shuttle-boxes directly from a filling-supply, and I desire to claim this feature broadly however carried 60 out.

Instead of providing the binder with a throat I may provide means for lowering or raising the binder when a filling-carrier is to be put in the shuttle-box.

65 Instead of giving to the boxes at the filling-changing end of the loom a quick rise and fall, as stated above, to insure the proper po-

sitions of the shuttle-box to receive another filling-carrier I may, when the detector indicates for a change of filling and after the 70 shuttle which has caused the indications has been thrown through the shed to the magazine end of the lay, disconnect the picking-motion and prevent any shift of shuttle-boxes on the next forward-and-backward stroke of 75 the lay and at the same time disconnect the box-motion and stop the harness-chain, so that on the next backward stroke of the lay the same shed as the previous one will be formed, I thereby holding in reserve the 80 proper shed. Now by allowing the box-motions to shift the boxes during the next backward motion of the lay after replenishment of filling should the box-pattern call for a different shuttle than the one previously thrown 85 and just replenished with filling and by allowing on the next backward stroke of the lay after replenishment of filling the shed-motion to form the shed held in reserve the picking-motion may then be put into action 90 and throw the shuttle in the line of the race-way when the lay reaches on its backward stroke the proper picking position. The shed and box motions are stopped by stopping the chains and are started by restarting the same. 95 The indications for these three motions are made simultaneously; but the motions themselves act independently as timed in looms of ordinary construction of this class.

While I have shown and described the electric circuit, contact-plates, and coöperating parts for calling the filling-changing mechanism into operation to effect a change of filling, it is to be understood that my invention is not limited thereto; but any appropriate 105 device, either electrical or mechanical, may be employed for this purpose.

When in the specification and claims reference is made to a filling-changing mechanism or a change of filling, it is to be understood that I mean either devices to effect a 110 change of filling-carrier in the shuttle or devices that change the shuttles.

It is obvious that filling stop-motions such as commonly in use on all looms having shuttle-boxes at both ends of the lay may be utilized to set the filling-changing mechanism, and by the term "practical exhaustion," as used herein, I include also complete exhaustion.

Having thus described my invention, what I claim, and desire to secure by Letters Patent, is—

1. In a loom, the following instrumentalities, viz: a lay, shifting shuttle-boxes at each 125 end thereof, a filling-changing mechanism and provisions for rendering the filling-changing mechanism operative to effect a change of filling on the practical exhaustion of the filling in any of the shuttles.

2. In a loom, the following instrumentalities, viz: a lay, shifting shuttle-boxes at each end thereof, a filling-changing mechanism adjacent the shuttle-boxes at one end of the

lay and provisions adjacent the shuttle-boxes at the opposite end of the lay for rendering the filling-changing mechanism operative to effect a change of filling when that in any 5 shuttle has become practically exhausted to a predetermined amount.

3. In a loom, the following instrumentalities, viz: a lay, shifting shuttle-boxes at each end thereof, a filling-changing mechanism 10 adjacent the shifting shuttle-boxes at one end of the lay, a filling-detector, and means operative through the detector on practical exhaustion of the filling in an active shuttle to effect a change of filling.

15 4. In a loom, the following instrumentalities, viz: a lay, shifting shuttle-boxes, a filling-changing mechanism adjacent to the shuttle-boxes at one end of the lay, an electric circuit including an electromagnet, means 20 under control of the electromagnet for rendering the filling-changing mechanism operative to effect a change of filling, and devices for completing the circuit and energizing the magnet on the practical exhaustion of 25 the filling in any of the shuttles.

5. In a loom, the following instrumentalities, viz: a lay, shifting shuttle-boxes at each end thereof, a filling-changing mechanism adjacent the shifting shuttle-boxes at one end of 30 the lay, an electric circuit including an electromagnet, electric terminals or contact plates, means for completing the circuit through said terminals on the exhaustion of the filling in a shuttle to a predetermined 35 amount, and devices under control of the electromagnet for rendering the filling-changing mechanism operative to effect a change of filling.

6. In a loom, the following instrumentalities, viz: a lay, shifting shuttle-boxes at each 40 end thereof, a filling-changing mechanism adjacent the shuttle-boxes at one end of the lay, an electric circuit including an electromagnet, electric terminals adjacent the shuttle-boxes at the other end of the lay, contact-fingers carried by the last-named boxes and adapted to complete the circuit on the exhaustion of the filling in an active shuttle to a predetermined amount, and means under 45 control of the said magnet to render the filling-changing mechanism operative to effect a change of filling.

7. In a loom, the following instrumentalities, viz: a lay, a set of shuttle-boxes carried 55 at one end thereof, a magazine adjacent said boxes, an electric detecting device at the opposite end of the lay from the magazine, and devices movable to operate the filling-changing mechanism.

60 8. In a loom, the following instrumentalities, viz: a lay, a set of shifting shuttle-boxes carried thereby, a filling-changing mechanism adjacent said boxes, and devices to effect a change of filling in the active box of the set 65 of shuttle-boxes when the filling in the active shuttle has become substantially exhausted.

9. In a loom, the following instrumentalities, viz: a lay, a set of shifting shuttle-boxes carried thereby, a filling-changing mechanism adjacent said shifting shuttle-boxes, 70 means to shift said boxes and to position them for a change of filling, and devices to effect a change of filling in the active box of the set of shifting shuttle-boxes when the filling in an active shuttle has become practically exhausted. 75

10. In a loom, the following instrumentalities, viz: a lay, a set of shifting shuttle-boxes carried thereby, a filling-changing mechanism, adjacent said shifting shuttle-boxes, 80 means to shift said boxes on the backward movement of the lay and to maintain them in position for a change of filling on forward movement thereof, and means to render the filling-changing mechanism operative to effect a change of filling when that in an active shuttle has become practically exhausted. 85

11. In a loom, the following instrumentalities, viz: a lay, shifting shuttle-boxes at each end thereof, a filling-changing mechanism 90 adjacent the shifting shuttle-boxes at one end of the lay, means for indicating a practical exhaustion of filling in the shifting shuttle-boxes at the opposite end of the lay, and devices to effect a change of filling in the active 95 box of the shuttle-boxes on the filling-changing end of the lay, when the filling in an active shuttle has become practically exhausted.

12. In a loom, the following instrumentalities, viz: a lay, a set of shifting shuttle-boxes 100 at each end thereof, means for raising or lowering one set of said boxes between the picks and for raising or lowering the other set on the backward movement of the lay, filling-changing mechanism adjacent the last-named 105 set of boxes, and means to operate the said mechanism to effect a change of filling.

13. In a loom, the following instrumentalities, viz: a lay, a set of shifting shuttle-boxes carried thereby, means for shifting said boxes, 110 a filling-feeder adjacent said boxes, connections between the said means and the filling-feeder to move the latter in unison with the shuttle-boxes, and devices rendered operative on the practical exhaustion of the filling 115 in an active shuttle to effect a change of filling.

14. In a loom, the following instrumentalities, viz: a lay, a set of shifting shuttle-boxes carried thereby, a filling-feeder adjacent said shuttle-boxes, a transfeerer to transfer a supply 120 of filling from the feeder into a box of the set of shifting shuttle-boxes, and means to operate the transfeerer on the practical exhaustion of the filling in an active shuttle.

15. In a loom, the following instrumentalities, viz: a lay, a set of shifting shuttle-boxes carried thereby, a filling-feeder carrying groups of filling-supplies adjacent said shifting shuttle-boxes, means to transfer a supply 125 of filling from the feeder into a cell of the set 130 of shifting shuttle-boxes, and devices made operative on movement imparted by the trans-

ference of filling to cause the filling-feeder to bring a different group of filling-supplies in position for the subsequent action.

16. In a loom, the following instrumentalities, viz: a lay, a set of shifting shuttle-boxes carried thereby, a filling - feeder carrying groups of filling-supplies adjacent said boxes, means for shifting said boxes, connections between said means and filling-feeder to move 10 the same in unison with the boxes, means to supply filling to the shuttle-box, and devices made operative by the transference of filling to cause the filling-feeder to bring a different group of filling-supplies into position for a 15 subsequent transfer of filling.

17. In a loom, the following instrumentalities, viz: a lay, a set of shifting shuttle-boxes at each end thereof, a filling-changing mechanism adjacent the shifting shuttle-boxes at 20 one end of the lay, a pair of contact-plates or terminals adjacent the shuttle-boxes at the other end of the lay, contact-fingers carried by each box of the last-named set of shuttle-boxes adapted to engage the said contact- 25 plates or terminals as each box moves into the line of the race, an electric circuit, means under the control thereof for operating the filling-changing mechanism, and a detector to complete the circuit when the filling in a 30 shuttle in use has become practically exhausted.

18. In a loom, the following instrumentalities, viz: a lay, a set of shifting shuttle-boxes carried at each end thereof, a filling-changing mechanism adjacent the shuttle-boxes at 35 one end of the lay, means adjacent the opposite end of the lay operative on practical exhaustion of the filling in an active shuttle to actuate the filling-changing mechanism and 40 effect a change of filling when the shuttle has reached the filling-changing end of the lay.

19. In a loom, the following instrumentalities, viz: a lay, a set of shifting shuttle-boxes at each end thereof, a filling-changing mechanism adjacent the shuttle-boxes at one end of the lay, an electric circuit including an electromagnet and contact-plates or terminals adjacent the shuttle-boxes at the opposite end of the lay, contact-fingers carried by each 45 box of the last-named set of boxes adapted to contact with said plates or terminals and complete the circuit through an active shuttle when the filling thereof is practically exhausted, and means under control of the electromagnet to render the filling - changing mechanism operative to effect a change of filling when the practically exhausted shuttle has reached the changing end of the lay.

20. In a loom, the following instrumentalities, viz: a filling-feeder, carriers arranged 60 therein in groups, means to transfer the same, and means also to actuate said feeder for a distance equal to the distance apart of like fillings in the different groups, and devices 65 for rendering the said means operative by the transference of filling.

21. In a loom, the following instrumentalities, viz: a filling-feeder, carriers arranged therein in groups, a transerrer, a pinion carrying a yoke, connections between the pinion and filling-feeder, said yoke being connected to the transerrer, and means to turn said pinion on movement of the yoke by the transerrer during the change of filling. 70

22. In a loom, the following instrumentalities, viz: a lay, a set of shifting shuttle-boxes carried thereby, a filling-changing mechanism adjacent said boxes, a single binder for said shuttle-boxes, and means to operate the filling-changing mechanism to effect a change 80 of filling when that in any shuttle has become practically exhausted. 75

23. In a loom, the following instrumentalities, viz: a lay, a set of shifting shuttle-boxes carried thereby, a single binder made rigid in 85 the line of the raceway, and means to raise and lower the boxes past the binder.

24. In a loom, the following instrumentalities, viz: a lay, a set of shifting shuttle-boxes carried thereby, a single slotted binder stationary in the line of the raceway, means to shift the boxes behind the binder, and devices for passing a filling-carrier through the slot of the binder. 90

25. In a loom, the following instrumentalities, viz: a lay, a set of drop-boxes carried thereby, a single binder made rigid in line of the raceway, and means to operate said binder to lift it from contact with the shuttles at the proper times. 95

26. In a loom, the following instrumentalities, viz: a lay, a set of drop-boxes open at the front and rear for the reception and discharge of filling, fixed guides passed through the boxes in position to retain the shuttles 100 therein, and means for raising and lowering the boxes.

27. In a loom, a lay having a series of shifting shuttle-boxes at each end thereof, electric detecting means occupying a position substantially in line with the raceway of the lay, said detecting means coöperating with the shuttle in either cell of the shuttle-box, whichever cell is in operative position at the raceway. 110

28. In a loom, a lay, a shifting shuttle-box at the detecting end of the lay, a plurality of binders carried by said shuttle-box, contact-fingers carried by said binders, contact-plates or terminals sustained by the lay and located 115 at substantially the level of the raceway of the lay, and means to move said shuttle-boxes and put one or the other of its cells at the level of the raceway of the lay, the contact-fingers of each of said binders meeting successively the contact-plates or terminals of the lay to effect a change of filling when the filling in the shuttle to be thrown has been practically exhausted. 120

29. In a loom, a shifting shuttle-box having 130 a series of cells open at front and rear, a binder coöperating with one or the other cell

of the shuttle-box, and means to retain in their cells the shuttles not acted upon by said binder.

30. In a loom, a shuttle-box having cells open at front and rear, a binder having an opening of a size to permit the passage of a filling-carrier through the same, and a trans- 5 ferrer operative when the shuttle in the shuttle-box is practically exhausted.

31. In a loom, a shuttle-box having unob- 10 structed opposite portions, a lay provided with picker-guiding rods, separated one from the other sufficiently to enable the passage be- 15 tween them of a filling-carrier ejected from the shuttle-box.

32. In a loom, a lay, a shuttle-box open at both sides for the passage of a filling-carrier, and picker-guiding rods separated one from the other sufficiently to enable the passage be- 20 tween them of a filling-carrier ejected from the shuttle-box.

33. In a loom, a lay having a shifting shuttle-box open at front and back, a coöperating binder having an opening for the passage of filling therethrough, and picker-guiding rods separated one from the other sufficiently to enable the passage between them of a filling-carrier ejected from the shuttle-box. 25

34. In a loom, a lay, a shifting shuttle-box having a series of cells open at back and front, picker-guiding rods, a binder having a passage therethrough for a filling-carrier, and a transerrer to feed filling through said binder into a shuttle in a cell of said shuttle- 30 box and to discharge the exhausted filling-carrier from the shuttle in the shuttle-box and through the space between said rods.

35. In a loom, a lay having shifting shuttle- 35 boxes at both ends, the boxes at one end of the lay having a binder for each cell, a series of shuttles open front and back, the shuttle-boxes at the opposite end of the lay having a single binder engaging one after another the different shuttles inserted in its box when brought into the line of the race of the lay. 40

36. In a loom, the following instrumentalities, viz: a lay having a set of shifting shuttle-boxes at each end, means to shift said shuttle-boxes according to the pattern being 45 woven, means to indicate that filling in a shuttle-box has been practically exhausted, and means to bring the boxes to the front center stationary, where, at a preceding beat, an indication was made that filling must be changed, and means to change the filling at a 50 beat of the lay following the beat in which the indication was made.

37. In a loom, a lay having a set of shifting

shuttle-boxes at one end arranged with a single binder, a filling-supply adjacent to the 60 shuttle-boxes, and means to transfer a filling-carrier from said filling-supply into the cell of the shuttle-box then in the line of the race-way of the lay.

38. In a loom, a lay having a set of shifting 65 shuttle-boxes at the receiving end of the lay, means at the opposite end to indicate the practical exhaustion of filling, and means ad- 70 jacent the set of shuttle-boxes at the filling-re- ceiving end of the lay to transfer a filling-car- 75 rier to an active shuttle, and suitable means to feed the shuttle automatically.

39. In a loom, a lay having a set of shifting shuttle-boxes at each end thereof, a series of self-threading shuttles, a magazine located at 75 one end of the lay and containing filling to be supplied to the shifting shuttle-boxes at that end of the lay, means coöperating with the shuttle-boxes at the opposite end of the lay to indicate the practical exhaustion of fill- 80 ing, a transerrer to transfer a filling-carrier from the magazine into a shuttle in the cell of the shifting shuttle-box then at the level of the race of the lay.

40. In a loom, a lay having parallel picker- 85 guiding rods, a picker mounted on said rods, a shifting shuttle-box with any cell of which said picker may coöperate, and means to move said picker.

41. In a loom, a filling-supply mech- 90 anism, a lay, a series of shifting shuttle-boxes carried thereby at both ends having binders to retain the shuttle in proper position, elec- 95 trical means to set the filling-supply mechanism to change the filling and to break the in- dication in case the boxes shift.

42. In a loom, a lay, a shuttle-box attached thereto having a binder and insulated contacts carried by the binder to electrically set a device to cause new filling to be supplied 100 to a shuttle open back and front.

43. In a loom, a lay, a series of shifting shuttle-boxes carried thereby, a magazine ad- 105 jacent the shuttle-boxes, electrical means to set the filling-supply to change the filling and to reset the indication mechanism when the practically exhausted shuttle returns to the indicating position in line of the raceway.

In testimony whereof I have signed my name to this specification in the presence of 110 two subscribing witnesses.

RANDOLPH CROMPTON.
